[57] **CLAIM**

The ornamental design for an enclosure for an exercise apparatus, as shown and described.

DESCRIPTION

FIG. 1 is a first front perspective view of an enclosure for an exercise apparatus showing our new design;

FIG. 2 is a first right side elevational view thereof;

FIG. 3 is a first left side elevational view thereof;

FIG. 4 is a first front elevational view thereof;

FIG. 5 is a first rear elevational view thereof;

FIG. 6 is a first top plan view thereof;

FIG. 7 is a first bottom plan view thereof;

FIG. 8 is a second front perspective view thereof;

FIG. 9 is a second right side elevational view thereof;

FIG. 10 is a second left side elevational view thereof;

FIG. 11 is a second front elevational view thereof;

FIG. 12 is a second rear elevational view thereof;

FIG. 13 is a second top plan view thereof; and,

FIG. 14 is a second bottom plan view thereof.

The broken line are for illustrative purposes only and form no part of the claimed design.
